UNITED STATES PATENT OFFICE

102,147

DESIGN FOR A SHOE

Murray J. Rosenthal, Lynn, Mass.

Application September 29, 1936, Serial No. 65,043

Term of patent 3½ years

To all whom it may concern:

Be it known that I, Murray J. Rosenthal, a citizen of the United States, residing at 10 Beede Avenue, Lynn, Massachusetts, have invented a new, original, and ornamental Design for Shoes, of which the following is a specification, reference being had to the accompanying drawing forming a part thereof, in which:—

The essential features of the design of the present invention are the contour and shape of the shoe.

I claim:—

The ornamental design for a shoe substantially as shown and described.

MURRAY J. ROSENTHAL.
